BEVERAGE CONTAINER

Charles F. Wallace, Westfield, N. J., assignor to
Novadel-Agene Corporation, Belleville, N. J., a
corporation of Delaware

Application December 7, 1937, Serial No. 178,476

2 Claims. (Cl. 257—15)

This invention relates to beverage containers, and more particularly to shipping and dispensing containers of the kind shown and described in the Schulse U. S. Patent No. 2,051,013, that is, containers having permanently installed therein a conduit for the circulation of a cooling fluid for cooling the contained beverage preparatory to and during the dispensing of the beverage, and, if desired, during storage.

The invention aims to provide an improved shipping, cooling and dispensing container of the kind and having the advantages of the container shown in the Schulse patent, and having the additional advantage that the possibility of displacement of the coil or of failure of the tube by either transverse breaking or by splitting is reduced, permitting the coil tube to be made of less expensive material without reducing its useful life.

To these ends, I shape the tube forming the cooling fluid conduit to form two coils which under pressure therein tend to unwind in the same direction; an open bend or loop connecting one end of the coils, and two spaced supporting legs each extending from the other end of one of the coils. The supporting legs are thus both relatively short since each of them comes from the top of a coil and not one from the top and one from the bottom as with the single coil of the container shown in the Schulse patent. Most desirably, the coil tube is shaped in the form of a double helix consisting of two concentric coils connected from opposite sides of the coils by an S, or reverse, bend, the tube winding in a downward direction from one supporting leg toward the bottom of the keg or other container, then forming a reverse bend, and then winding in a reverse direction upward, and the other supporting leg extending from the top of this second coil. The two coils thus wind in the same direction from the supporting legs downward, or from the reverse bend upward.

By eliminating the long supporting leg, the greater stress or bending moment at and near the point of support of such long leg at the head or wall of the keg due to the greater leverage is avoided; and if liquid is permitted to freeze in the coils of an empty container, the tendency to unwind due to the expansion of the liquid as it freezes is equal and in the same circumferential direction in the two coils, and as the lower ends of the coils are free to make such movement there is no such stress-developing resistance as in the case of a coil restrained at both ends. When the connecting bend is a reverse bend ex-

tending from opposite sides of the coils, it will follow the circumferential movement of the coil ends by an angular movement. The new double coil conduit will also withstand without splitting a greater number of freezings of contained liquid. The open bend connection between the lower ends of the coils is of advantage in reducing the liability of splitting under the pressure of freezing liquid therein and in avoiding the excessive internal stresses which would be set up by making a sharp bend in the tube.

Another advantage of the invention is that after the coiled tube is attached to a container wall the coils may be stretched out axially to lengthen them or pressed together to shorten them. A keg head having the double coil tube mounted thereon may thus be used in kegs of somewhat different depth, the coils being readily lengthened or shortened as may be necessary or desirable.

An illustrative embodiment of the invention is shown in the accompanying drawing; in which

Fig. 1 is a sectional view of a wooden beer keg equipped with a double helix coil according to the invention, the coil being shown in elevation; and

Fig. 2 is a bottom plan view of the coil.

Referring to the drawing, Fig. 1 shows a wooden beer keg 10 having its upper head 11 provided with the usual draft bung 12, and having the usual filling bung 13 in the side wall of the keg 30 midway between the upper and lower heads.

Mounted within the keg is a cooling conduit formed by a tube of suitable metal or other suitable heat-conductive material shaped to provide two spaced supporting legs 20 and 21 and two helical coils, one, 22, winding downward from the leg 20 and the other, 23, winding downward in the same direction from the leg 21, and the lower ends of the two coils being connected from opposite sides of the coils by a reverse bend 25. The coils are, most desirably and as shown, of substantially the same diameter with the same number of turns and having turns of each extending between turns of the other and spaced apart. The coils are permanently installed in, or built into, the keg by having the two supporting legs 20 and 21 secured to fittings, or adaptors, 26 and 27 set in openings in the keg wall, most desirably, and as shown, in the upper head 11 one on each side of the draft outlet in a diametrical plane at right angles to the axis of the filling bung. Any suitable connecting means may be provided for connecting the outer ends of the supporting legs to the keg wall to securely hold the leg ends and to provide for connection thereto of means, such

as the branch connections from the cooling fluid mains of the circulating system of the Schulse Patent 2,051,013, for the supply and return of the cooling fluid. As shown, the adaptors to which the leg ends are connected are formed by bushings secured in openings in the keg head by threaded collars or nuts 28 which also serve to receive threaded connections of the cooling fluid supply and return lines. The ends of the two legs 20 and 21 extend into the adaptor bushings and are expanded or otherwise secured therein.

The coils, supporting legs and reverse bend of the cooling conduit are most desirably made from a single piece of tubing of a suitable strong metal, such as certain copper alloys coated on the outside with silver or tin, and of suitable size and wall thickness and length to have the necessary strength and to provide the required amount of cooling surface. The coils should, most desirably, be positioned in the lower half of the container in order that the major cooling area shall be near the bottom of the container, from where the beverage is drawn, and in a shipping keg such as shown the coils should be below the filling bung in order to avoid interference with the conventional filling or racking tube. With the supporting legs 20 and 21 connected to the upper keg head in a diametrical plane at right angles to the axis of the filling bung, as shown, there will be no interference with the racking tube by the supporting legs. With the coils and supporting legs arranged as shown there will also be no interference with the usual draft tube inserted through the draft bung in the top head of the keg, and in order that the draft tube may extend clear to the bottom head, the reverse bend of the cooling conduit is set off to one side of the center.

The size and length of the tube forming the cooling conduit will, of course, vary for different containers and for different cooling fluids to be circulated through the conduit. For wooden beer kegs of the conventional size of 15½ gallons

capacity, for use in a cooling system in which the cooling fluid is water at a temperature close to the freezing point, entirely satisfactory results have been obtained with the conduit made of silver plated copper alloy tubing having an outer diameter of $\frac{5}{8}$ inch and a wall thickness of .042 inch, and a total length of somewhat over 14 feet.

What is claimed is:

1. A shipping, cooling and dispensing beverage container, having as a permanent part thereof a coiled tube of heat-conductive material mounted therein for the circulation of a cooling fluid for cooling contained beverage, in which the cooling fluid tube is shaped to form two helical coils connected at one end by an open reverse bend and winding both in the same direction from the connecting reverse bend and two spaced supporting legs of substantially equal length extending one from the other end of each of the coils and from opposite sides of the coils, the outer ends of said legs being secured at spaced points to a wall of the container to support the coils and to provide inlet and outlet terminals for admission and discharge of the cooling fluid.

2. A shipping, cooling and dispensing beverage container, having as a permanent part thereof a coiled tube of heat-conductive material mounted therein for the circulation of a cooling fluid for cooling contained beverage, in which the cooling fluid tube is shaped to form two concentric helical coils of the same pitch and diameter connected at their lower ends by an open reverse bend and winding upward both in the same direction and two spaced supporting legs of substantially equal length extending upward one from the upper end of each of the coils and from opposite sides of the coils, the upper ends of said legs being secured at spaced points to a wall of the container near the top thereof to support the coils and to provide inlet and outlet terminals for admission and discharge of the cooling fluid.

CHARLES F. WALLACE.
